(57) **CLAIM**

The ornamental design for a yarn ball winder, as shown and described.

DESCRIPTION

FIG. 1 is a perspective view of a yarn ball winder showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 in FIG. 1; and,

FIG. 10 is a partial enlarged view of portion 10 in FIG. 1.

The broken lines in the drawings illustrate the portions of the yarn ball winder, which form no part of the claimed design. The dot-dash broken lines in FIG. 1 represent the boundary of the enlarged portion and form no part of the claimed design.
